CENTRIFUGAL PUMP

Charles Harold Warman, Kalgoorlie, Western Australia, Australia

Application December 29, 1939, Serial No. 311,680
In Australia January 10, 1939

3 Claims. (Cl. 103—103)

This invention relates to improvements in centrifugal pumps: more particularly to improvements in pumps for use in pumping corrosive fluids or fluids with abrasive solids in suspension. A great difficulty in pumping fluids of this nature is to prevent wear and consequent enlargement of the clearances between the rotary and stationary members, which will result in leakage, slippage, and serious loss of head and efficiency.

The chief object of my invention is to provide improved durable and efficient sealing means for preventing the passage of fluids between the stationary and rotary members. Another object is to provide a pump which is simple, easily accessible, and with few parts subject to corrosion and/or abrasion by the fluids being pumped.

My invention is illustrated more or less diagrammatically in the accompanying drawing, wherein:

Fig. 1 is a part vertical axial section.

Fig. 2 is a section on a smaller scale on the line 2—2 of Fig. 1.

Fig. 3 is an elevation of the expeller member, also on a smaller scale.

Like parts are illustrated by like characters throughout the specification and drawing.

Referring to the drawing, 10 generally indicates a frame. It supports a bearing housing 11, of any suitable design for rotatably mounting the spindle 12. The frame has attached a vertical portion or frame plate 13, having a circular recess for a renewable resilient liner 14, and an annular flange projecting from one side of the casing 15. The casing is held in place on its plane surface against the resilient liner by studs 16, screwed into the frameplate 13, and passing through the coverplate 17, which also has a circular recess for a renewable resilient liner 18. Two of the studs 16, diametrically opposite each other, may each have an intermediate nut, not shown, which tightens against the lugs (also not shown) on the casing 15, and serves to hold it in position when the coverplate 17 is removed.

An impeller 19 is situated concentrically within the casing 15, and has an axial intake opening and peripheral discharge ports. It has a boss 19' passing with working clearance through a central aperture in the liner 14, such boss being provided with a taper bore seating on the tapered portion of the spindle 12 and removably secured thereto by the setscrew 20, which has a square head, engaging a suitable corresponding recess in the impeller. The direction of rotation of the impeller (anti-clockwise when

viewed as in Fig. 2) is such that the setscrew tends to screw into the spindle 12 when the pump is in operation. On each of its outer faces, the impeller 19 is provided with a plurality of projections or vanes 21, outwardly conforming with suitable working clearance to the liners 14 and 18 respectively.

The casing 15 is provided with an annular recess 22, of constant cross-section, from which 10 the outlet branch 23 develops tangentially and upwardly diverges to give a circular cross-section at the outlet flange. This flange has an annular groove 23' adapted to receive a packing ring, and delivery piping may be attached 15 in any suitable manner.

Provided on the coverplate 17, is the axial intake branch 24, having a flange of any suitable design for attachment of the inlet piping. The renewable resilient liner 18 has an axial tubular portion 18' adapted to fit closely inside the intake branch 24, to prevent wear by the material flowing into the pump. An annular axial inner tubular projection or extension 18' of the liner 18 has its outer cylindrical surface conforming 20 to the vanes 21 with suitable working clearance. This serves to direct the flow of material pumped into the intake opening of the impeller 19.

The frameplate 13 is provided with a central 30 cylindrical portion, adapted to receive internally a circular die plate 25 and an outwardly cylindrical liner 26, both of which are held in position by being clamped between the renewable resilient liner 14 and a shoulder 37 on the frame plate 13. An inwardly projecting diaphragm 38, part of the cylindrical liner 26, has a central circular aperture, through which the rotating members pass with ample working clearance. It also has an extension on the 35 diaphragm portion in the form of a central projecting annular shoulder 39. The renewable resilient liner 14 consists of a rigid circular plate, having a central projecting tubular portion 40. It is completely covered with a resilient wear 40 resisting material, such as, for instance, soft rubber, which may be moulded about it. Its central aperture allows the impeller boss 19' to pass through it with ample working clearance. To the outer cylindrical surface of the resilient 45 covering on said projecting tubular portion 40 of the liner 14, the vanes 21, on the impeller 19, conform with suitable working clearance.

Mounted on the spindle 12, and rotating with it, are an auxiliary impeller or expeller 27, a 50 pliable elastic disc sealing member 28, a scaling

disc follower 29, and a helical spring 30. This spring, being mounted in a state of compression between the fixed shaft collar 31 and the sealing disc follower 29, forces the expeller member 27 against the impeller boss 19', the sealing disc 28 against the said expeller member, and the sealing disc follower 29 against the said sealing disc. The sealing disc member 28 consists of a flat disc of a pliable elastic material, such as sheet rubber, having a central circular aperture somewhat smaller in size than the spindle 12. When distended to fit over said shaft and clamped tightly by spring pressure between the convex conical surface of the sealing disc follower 29 and the concave conical surface of the expeller 27, such sealing member assumes a conical form, and in so doing contacts and forms a continuous circumferential seal with the conical surface of the die plate 25, when the spindle 12 is not rotating. When the spindle 20 rotates at an appropriate speed, centrifugal force acting on the conical sealing member 28 causes it to become less conical, so that it ceases to contact the die plate 25, and rubbing contact between the stationary and rotating members is avoided. Situated within and conforming with ample running clearance to the annular space between the diaphragm portion of the liner 26 and the liner 14, are the radial flange and the sloping expeller vanes 32, forming part 30 of the expeller member 27. The expeller vanes project axially and overlap the annular shoulder on the diaphragm portion of the liner 26. A dowel or key 33, projecting from the spindle 12, and engaging a recess provided for it in the 35 expeller 27, insures that the expeller will rotate with the shaft.

To facilitate the machining and manufacture of the impeller 19 and expeller 27, which are made of a hard material to withstand wear and abrasion, the portions which fit the spindle 12 are lined with a soft non-corroding material 34 and 35, such as white metal, such lining also facilitating the removal of these members when their replacement is required.

The use and operation of my invention are as follows:—

With the pump constructed as shown in the drawing, the impeller is caused to rotate in an anti-clockwise direction, and the fluid to be pumped permitted to flow into the impeller intake through the intake branch 24. Passing through the impeller discharge ports, the fluid has its pressure increased by centrifugal action to that within the casing 15, adjacent to the periphery of the impeller. On leaving the impeller, the fluid continues to rotate within the casing, developing further pressure with decrease of its kinetic energy, until it is discharged through the outlet branch 23 into a delivery pipe or the like.

Leakage of fluid discharged from the impeller back to the intake opening and at the point where the impeller boss passes through the liner 14 respectively, is almost entirely prevented by the centrifugal action on the fluid of the vanes 21 projecting from the sides of the impeller co-acting with the projecting shoulders of the liners 18 and 14 respectively. These shoulders direct the slippage fluid inwards in the path of the vanes 21, which return it to the periphery of the impeller. Freedom from leakage, where the rotating members pass through the frame plate 13 is ensured when the pump is operating, by the expeller member 27 rotating within the space 70 between the diaphragm portion of the liner 26

and the liner 14, and so creating by centrifugal action of the vanes 32 on the slippage fluid a pressure therein equal to that at the point where the impeller boss passes through the liner 14.

5 The annular shoulder, part of the liner 26, about the outer cylindrical surface of which the vanes 32 rotate, serves to direct the slippage fluid in the path of said vanes. Leakage of fluid, where the rotating members pass through the frame plate 13, when the impeller is not rotating, is prevented by the continuous sealing contact of the pliable elastic disc sealing member 28 with the die plate 25, the fluid pressure within the pump acting to press said sealing member against the die plate. When rotating at the proper operating speed, the more or less conical sealing member 28 is flattened out by centrifugal force and runs clear of the die plate.

I am aware that centrifugal pumps are in use, or have been described, which have auxiliary impeller or expeller means for preventing by centrifugal action the leakage of fluid at the point where the impeller spindle enters the casing, and have also centrifugal means for sealing the clearance between the shaft and the casing when the pump is inoperative. In every case, however, the auxiliary impeller or centrifugal sealing devices and the impeller spindle have been placed on the intake or suction side of the main impeller, where they are subjected to the pump intake head only, the path of entry of the fluid to the impeller being between the impeller and the centrifugal sealing means. My present invention differs basically from these pumps, in that the auxiliary centrifugal sealing means employed for preventing leakage of fluid where the impeller shaft enters the casing is on the side of the impeller opposite to its intake opening, and performs its duty of preventing leakage against the full pressure in the casing, by co-operating with auxiliary vanes projecting from the side of the impeller opposite to its intake opening and adjacent to the point of entry to the casing of the impeller supporting means.

40 I am aware also that many centrifugal devices are in use, or have been described, which employ impellers having projecting auxiliary vanes on the side of the impeller adjacent to the point of entry to the casing of the impeller spindle, said vanes being peripherally adjacent and exterior to cylindrical shoulders projecting from the casing. I make no claim to such devices, except in combination with separate auxiliary impeller means external to the main impeller chamber, such that the combined centrifugal effect of the auxiliary vanes on the main impeller and the auxiliary impeller means is sufficient to give a fluid pressure equal to or greater than the fluid pressure within the main impeller chamber.

55 I claim:

1. A centrifugal pump comprising a casing having a main chamber and an auxiliary chamber therein, a spindle extending through said auxiliary chamber into the main chamber of said casing, an impeller arranged within said main chamber and fixed to one end of said spindle, a boss formed with said impeller, a renewable liner arranged within said casing between the main and auxiliary chambers thereof, an annular projection formed with said liner extending about said boss and having a running clearance therewith, an auxiliary impeller arranged within said auxiliary chamber, vanes formed with said auxiliary impeller, and a cylindrical liner with an inwardly projecting diaphragm extending about

said vanes with a running clearance therebetween.

2. A centrifugal pump comprising a casing, a frame plate connected to said casing, a liner interposed between said frame plate and casing, one end of said frame plate having a circular opening formed therein, a spindle extending through the circular opening of the said frame plate, an impeller arranged within said casing and fixed to one end of said spindle, a boss formed with said impeller and extending through said liner arranged between said frame plate and casing, an auxiliary impeller connected to said spindle and arranged adjacent one end of said boss, a cylindrical liner slidably arranged within said frame plate adjacent said auxiliary impeller and a circular die plate with a central aperture having a running clearance with the spindle and

slidably arranged adjacent said cylindrical liner within said frame plate.

3. A centrifugal pump comprising a casing having a main chamber and an auxiliary chamber therein, a spindle extending through said auxiliary chamber into the main chamber of said casing, a die plate forming the end of said auxiliary chamber remote from said main chamber, a central aperture in said die plate through which said spindle passes with running clearance, a pliable disc sealing member mounted on said spindle adjacent said die plate within said auxiliary chamber, said pliable disc sealing member being adapted to be pressed in sealing contact with said die plate by fluid pressure within the auxiliary chamber when the pump is inoperative.

CHARLES HAROLD WARMAN.
